UNITED STATES PATENT OFFICE

JOHN J. GEIGER, OF NEW YORK, N. Y.

AUTOMATIC SWITCHING SYSTEM FOR TOY RAILROADS

Application filed August 11, 1931. Serial No. 556,449.

This invention relates to switching systems for toy railways and particularly to an automatic switching system wherein when the parts are properly set, a toy train may be 5 switched automatically from one series of tracks to the other as long as power is supplied.

An object of the invention is to provide a simplified construction for electrically operated toy trains wherein two or more tracks may be used and the trains automatically switched from one track to the other so that each train will successively pass over the various track systems.

15 Another object of the invention is to provide in an automatic switching system a switch adapted to be actuated by the engine of the train for turning on and off current to the switch operating mechanism, the same being associated with insulated rail sections for 20 providing current to the switch mechanism for automatically resetting the same.

In the accompanying drawings,

Figure 1 is a top plan view of a toy railroad disclosing a structure embodying most of the invention.

Figure 2 is a fragmentary perspective view showing the front part of an electric engine and part of the track together with a switch 30 and operating bar carried by the engine.

Figure 3 is a vertical horizontal sectional view through the switch shown in Figure 2, the same being on an enlarged scale.

Figure 4 is an enlarged top plan view of 35 one of the insulated sections shown in Figure 1, the same being shown in connection with a power take-off contact structure.

Figure 5 is a plan view of one of the switches and associated parts shown in Figure 1, the housing of the switch operating mechanism being shown in section for better illustrating the arrangement of conductors.

40 Referring to the accompanying drawings by numerals, 1 indicates a three rail track for toy railroads, the same being of a well known kind, as for instance the Lionel tracks as now commonly placed on the market. These tracks consist of suitable metallic ties 2, rails 3 and 4 for receiving the wheels of the engine and cars of the train placed on the track and

a central power rail 5. The rails 3 and 4 are connected to the tie 3 but not insulated therefrom. Rail 5 is connected with the respective ties 2 but is insulated therefrom so as to act as a third rail to supply power to the engine 55 5 through well known mechanism now in common use. This mechanism usually consists of a contact shoe which is electrically connected with the motor of the engine 6 and which has one side connected with the wheels 60 of the engine, said wheels resting on the rails 3 and 4. The structure just described is old and well known and forms no part of the present invention except in combination.

Associated with the tracks 1 are switches 7 and 8, said switches being of identical structure so that a description of one will apply to both. As these switches are old and well known structures as now found on the market, it is thought a detailed description thereof is not necessary. The particular switch shown in the accompanying drawings is the ordinary Lionel switch which is operated by a pair of solenoids 9 and 10 as shown in Figure 5, said solenoids having a core 11 connected by a rod 12 and by certain suitable connecting members with the plate 13. Plate 13 carries the rail sections 14 and 15 and also a central rail 16 which is insulated from plate 13. Plate 13 is pivotally mounted at 17 so that when the switch is set as shown in Figure 5, the train will take the side track, but if the switch is moved to the right as shown in Figure 5, the train will take the straight track. When the solenoid 10 is energized the switch is moved from the position shown in Figure 5 until rail 15 contacts with the rail 3. When solenoid 9 is energized the parts will function to swing the switch mechanism to the position shown in Figure 5. All the structure just described is old and well known except the detailed wires 18 and 19. It will be noted that these wires are connected to one end of the windings of the respective solenoids 10 and 11 and also connected to the rail 16. It will therefore be noted that one terminal of each of the solenoids is grounded on the power rail while the other terminals 20 and 21 are connected to the wires or other conductors 22 and 23. Conductor 22 is con-

nected through contact 24 to the insulated rail 25', said rail being identical with insulated rail 25 except that it is curved instead of straight. The rail 25 and associated parts are shown in Figure 4. From this figure, it will be seen that suitable insulation 26 insulates rail 25 from the various ties 2 and the connecting pins 27 of insulation insulate the rails 25 from the adjacent rails 3 of the track.

10 The contact 24' may be of substantially any desired kind, but as shown, consists of an insulating plate 28 carrying spurs 29 which press against the rail 5 and a swinging clamp 30 adapted to press against the rail 3. The clamp 30 is pivotally mounted on a metallic plate 31 which carries a terminal 32 to which a wire 33 is secured. The contact 24 is identical with the contact 24' and will, therefore, need no detailed description. Wire 33 is connected to the terminal 34 of the train operated switch 35 while the wire 36 is connected with the terminal 37 of switch 35 and also to the terminal 23' while the wire 37 is connected to the terminal 22' and to the contact 24".

15 Wire 23 is connected to a contact 24''''. It will be understood that the contacts 24' and 24''' are connected to the insulated rail sections 25'' and 25''' in a similar way to the connection shown in Figure 4. The switch 35 as shown particularly in Figures 2 and 3 is provided with a swinging arm 38 which is adapted to strike an abutment 39 formed of insulating material and bolted or otherwise rigidly secured to engine 6. Also, the abutment could be made from metal and insulated from the engine, the function of the abutment being to strike the rod 38 and swing the mechanism of switch 35 from one position to the other. The switch 35 is a well known structure now on the market and is commonly known as a pull switch. This form of switch when pulled or moved in one direction closes the circuit and when given a second pull opens the circuit. As this is an old and well known switch, the details thereof will not be described, but it will be understood that when the engine 6 passes the switch for the first time, the circuit will be closed between the wires 33 and 36. When the engine passes a second time in the same direction, the circuit between the wires 33 and 36 will be open. If the train should move in a reverse direction past switch 35, the switch will not be shifted but will remain in its original setting.

20 In operation, the engine or a train of cars including an engine is supplied with current when the parts are properly functioned, current being supplied from any suitable source through suitable wires 40 and 41. When the current is supplied and is turned on to the engine 6, the engine will begin to move, it being understood that most of the track 1 and the engine 6 are old and well known structures, for instance, the ordinary Lionel structure now in common use on the market,

Assuming that engine 6 is at point A in Figure 1 when the current is turned on, the engine would begin to move in the direction of arrow 42. As soon as the wheels begin to strike the section 25''' current will flow from rail 4 through the wheels and body of the engine to rail 25'', wire 37, wire 20, as shown in Figure 5, the windings of the solenoid 10, and, finally, through wire 18 to rail 16. This will cause the switch 8 to be moved over to the position shown in Figure 1 unless already in that position. The engine will continue without stopping and will pass on to the rail section 25''' whereupon the same action takes place, namely, current will pass from the rail 4, through the wheels and frame of the engine to the rail 25'''.

25 The current passing to the rail 25''' will pass through wire 23, wire 21, as shown in Figure 5, the windings of the solenoid 11, and wire 19 to rail 16 which is part of the power rail 5. This will cause the solenoid 11 to move the switch 7 to the position shown in Figures 1 and 5 unless already in this position. While this is taking place, the engine or train is still moving and will pass switch 7 and finally pass the switch 35. As the engine passes switch 35, abutment 39 will strike the rod or arm 38 and actuate switch 35 so that it connects wires 33 and 36. This connection does not result in turning on the current to any operating parts, but sets the circuit so that switch 8 may be swung to the opposite position to that shown in Figure 1 when the engine passes the insulated rail section 25. However, before passing this section, the engine naturally passes the rail section 25' and the parts function as described in regard to sections 25'' and 25''' so that current will pass through wire 22, wire 20 as shown in Figure 5, the windings of solenoid 10 and wire 18 to rail 16, whereupon the switch plate 13 and associated parts will be moved toward the right in Figure 5. The engine continues past the contact 24' and current will pass as heretofore described from track 4 through the wheels and body of the engine to rail section 25, wire 33, switch 35, wire 36 and through the proper solenoid at switch 8 to move the switch 8 to the position shown in Figure 5, whereupon the engine striking this switch 8 will pass again to point A and then over the same path as heretofore described. After the train passes the contact 24'' a second time, current will be supplied to wire 37 for shifting the switch 8 to the position shown in Figure 1. As the engine passes contact 24'' the current supplied will move switch 7 over to the position shown in Figure 1 and the engine will continue to pass switch 35. As the engine passes switch 35 the second time, it will swing the arm 38 and will open the switch so that the wires 33 and 36 are not electrically connected. The engine passing the contact 24 will supply

current to wire 22 for actuating switch 7 so that it will move to the right, from the position in Figure 1, so as to make the main line clear. As the engine passes contact 24' 5 nothing occurs as switch 35 is open and consequently the engine will pass switch 8 while it is still in the position shown in Figure 1 and will move around the portion B of the track 1 and will pass switch 7 and again 10 strike the rod 38 for closing switch 35. This will eventually cause the switch 8 to be moved to the left from the position in Figure 1 and switch 7 moved to the left or to the position shown in Figure 1, so that the train will 15 pass around past point A on its third trip, the trackage of point A presenting a siding or auxiliary trackage. As switch 35 is closed one time and opened another time the engine passes, switches 7 and 8 will be automatically 20 actuated so that the engine will make one complete trip around the main track and then a trip around the main track from switch 7 to switch 8 and through the auxiliary track past point A. The next trip will be around 25 the main track and so on. This action is continued as long as the power is turned on and switch 35 functions.

I claim:

1. An automatic switch system for toy rail- 30 ways including a main trackage, an auxiliary trackage connected at certain points with the main trackage, a switch at the point of connection of the auxiliary trackage with the main trackage, electrically operated means 35 for opening and closing said switches, means for supplying current to said electrically operated means, said means including insulated track sections over which the wheels of a train is adapted to pass and wiring connect- 40 ing said sections to the respective means for actuating the switches and a train actuated switch for opening the circuit of one of said means so that the switch operating means associated with one of the switches will not 45 function, thus causing the train to at one time pass around the main trackage and at another time to be switched on to the auxiliary trackage.

50 2. In an automatic switch system for a toy railroad, a main trackage over which an electrically operated toy train is adapted to move, said trackage having a pair of wheel tracks and a third rail for supplying current to the 55 train, an auxiliary trackage connecting certain parts of the main trackage and electrically operated switch at the juncture of said auxiliary trackage with the main trackage at each juncture, means for closing the 60 circuit of said switches by said train so as to move the switches back and forth so that the same will be opened and closed and an engine operated switch for opening one of said circuits whereby when the train is functioning, it will pass around said main trackage

on one trip and will switch off onto the auxiliary trackage on the second trip.

3. In an automatic switching system for electrically operated toy railways, a main trackage and an auxiliary trackage with a 70 switch at each end of the auxiliary trackage connecting the auxiliary trackage with the main trackage, electrically operated means for each switch, a shunt circuit for each of the electrically operated means, each of said 75 shunt circuits including an insulated rail section and a train operated switch for opening and closing the circuit of one of the electrically operated means of one of said switches, whereby a train operating on said track- 80 age will make one trip around the main trackage and then on the second trip will pass over the second trackage.

4. In an automatic switching system for toy electric railways, a main trackage, an 85 auxiliary trackage, a switch connecting said auxiliary trackage with the main trackage, electrically operated means for moving one switch to an open and closed position, a wire leading from said electrically operated 90 means, an insulated rail track section connected with said wire, said track section being part of said auxiliary trackage, conductors extending from said electrically operated means to said main trackage at one point, 95 said main trackage at said one point having an insulated wheel rail to which said conductors are electrically connected and a train operated switch interposed in said conductors for opening and closing the circuit there- 100 of whereby when said switch is closed, current will be supplied to close said switch as the train passes over the main line.

JOHN J. GEIGER.
